UNITED STATES PATENT OFFICE.

THOMAS T. GAFF, OF WASHINGTON, DISTRICT OF COLUMBIA.

EXPLOSION-ENGINE.

1,059,604.

Specification of Letters Patent. Patented Apr. 22, 1913.

Application filed January 4, 1910. Serial No. 536,294.

To all whom it may concern:

Be it known that I, THOMAS TRUEMAN GAFF, of Washington, in the District of Columbia, have invented certain new and useful Improvements in Explosion-Engines, of which the following is a specification.

My invention relates to that type of explosion engine in which air only is first introduced into the combustion chamber, and, then, into the otherwise closed chamber, a suitable quantity of combustible is injected. That this method of charging the explosion or combustion chamber—the cylinder of the engine—may be practised with advantage, it is desirable that the period of injection should terminate only shortly before the instant of ignition—that is to say, toward the end of the compression stroke of the piston, when the air in the cylinder is under high pressure; and the means of injection must provide for a constantly recurring delivery into the cylinder at this time, under a pressure higher than the cylinder pressure, of a definite though very minute quantity of the combustible, which quantity must not vary except at the will of the operator. To maintain proper delivery pressure under these conditions some form of force pump for a fluid combustible is necessary. Here a difficulty arises, more particularly in the case of those engines composed of a number of small cylinders operating at high speeds, such as are used on automobiles, aeroplanes, etc. If each cylinder of the multicylinder engine be fitted with its individual pump, and if the pump be made of a strength sufficient to withstand the high pressures it must engender, it reaches such a size that its smallest stroke delivers more combustible than can be consumed in the cylinder into which it is feeding. If on the other hand the size of the pump be so reduced as to permit it to deliver at any one stroke only so much combustible as the cylinder into which it is feeding can consume, this very smallness of the pump and its parts renders them so fragile, or difficult of constant reliable operation, or both, that it cannot properly serve its purpose. These difficulties are greatly magnified by the very high frequency of delivery required. A two cycle engine has a range of speed of from about 200 to 1200 revolutions per minute, and, at each revolution, it must be supplied with combustible. A single acting pump would, therefore, have to be capable of making up

to 1200 strokes per minute; a double acting pump half that number. If it be attempted to use a single pump for all the cylinders of a multicylinder engine of this type, the difficulty increases in proportion with the number of cylinders. A single acting pump under these conditions would have to be capable of making from 800 to 2800 strokes per minute.

It is one of the objects of my invention to avoid this prime difficulty. To that end I make use, in connection with a force pump, of an accumulator, fitted with a by-pass, and carrying a constant pressure against a valve interposed between the accumulator and the engine, which valve is so constructed and combined with means for periodically operating it as to admit at any desired time any desired quantity of the combustible from the accumulator into the cylinder of the engine, at any necessary pressure. In this way the difficulty I have above referred to is entirely overcome. The pump can be of such size as to insure adequate strength. Any excess of fluid pumped by it, instead of going to the cylinder, is returned through the by-pass of the accumulator mediately or immediately to the pump, while the amount of combustible admitted to the cylinder is governed by a valve which is effective to control the injection of minute quantities under considerable pressure, and responds quickly and accurately to the influence of the operating agencies employed in connection with it for this purpose. This, and other features of my invention, will be readily understood by reference to the accompanying drawings.

In said drawings—Figure 1 is a side elevation—largely diagrammatic and divested of structural detail—of a single cylinder explosion engine, of the type known as two cycle or two stroke cycle, fitted with devices embodying my invention in simple form. The accumulator is shown in section. Fig. 2 is a like view of a multi-cylinder engine of the same type fitted with more elaborate devices embodying my invention. Fig. 3 is an axial section through the electro-magnetic valve and its casing interposed between the accumulator and the cylinder. Figs. 4, 5, 6, 7, are views representing the structural details of the device, whereby the action of the electro-magnetic valve is controlled. Fig. 4 is a side elevation on enlarged scale of the device. Fig. 5 is a plan of the same

with the cover of the inclosing cylindrical case or box removed. Fig. 6 is a developed plan of the series of insulated contacts which extend around and are fast to the inside wall of the case. Fig. 7 is an axial section on line 7—7, Fig. 5, with the cover of the case in place.

The device shown in Figs. 4—7 is in the nature of a "timer" for the injection valve. 10 It is designed for a six cylinder engine, and for this purpose has six insulated contacts on the interior of its shell. But the principle of its action is the same whether one, two or more contacts are employed, the number of contacts depending upon the number of cylinders the engine has.

Confining attention for the present to Fig. 1—A is the cylinder of a two cycle engine having the usual water pump W for 20 circulating cooling water. B is an accumulator having an internal head b backed by a spring b' which resists the tendency of the entering fluid to force back the head b. C is the force pump by which the combustible fluid is forced into the accumulator through connection c, compressing the spring b' until the fluid in the accumulator has attained the desired degree of pressure (which of course should be sufficient 25 to overcome the pressure in the engine cylinder A). The accumulator is fitted with a by-pass H, which returns directly to the pump C, as shown. The pump is driven by any suitable means from the engine. I have here shown it driven by worm and gear X Y direct from the crank shaft of the engine the gear Y having a crank pin on it, connected by an intermediate connecting rod y to the piston rod i of the pump. A 30 pipe g leads from the accumulator to the engine cylinder, the inlet of said pipe into the cylinder being controlled by a valve G—in this instance an electro-magnetically operated valve. E is an ordinary ignition timer to control the spark, it being mounted, as usual, upon a vertical shaft I, driven from the crank shaft of the engine by suitable means, as by bevel gearing as shown. This spark timer is of any usual construction, and being well known to those skilled 35 in the art I have omitted its structural details as well as its battery and spark plug connections. D is the "timer" to operate the valve G; it also is mounted on the shaft I. F is a battery connected on the one hand 40 to the timer D and on the other hand to the electro-magnetic controller of valve G—the circuit being from one pole of battery to D, thence to ground, thence to G and thence 45 to opposite pole of battery. A manually operated switch s is interposed at a suitable point in the circuit.

There is the same general arrangement of parts in the two cylinder engine in Fig. 2, 50 and the parts there are identified by the

same reference letters as in Fig. 1. Each cylinder, A and A', respectively, has its own valve G and G', with a common connection to the accumulator B, and each valve has its own independent circuit connections with the valve timer D, and its own manually operated switch, s and s' respectively, for controlling the same, the valve circuit being from battery F through 7 to D, thence through s or s' to G or G', thence to ground, and thence back to battery F.

The procedure is as follows: Either by turning over the engine, or otherwise, the pump C, which is connected with any suitable source of fluid combustible supply, is operated until the desired pressure is reached in the accumulator B, the switch s at this time being open, and the valve G in consequence, remaining closed, although its chamber is now charged with fluid at accumulator pressure. Now, closing the switch s, and turning the engine over, the timer D, at the proper moment, completes the battery circuit, the electro-magnet of valve G 90 is energized and causes the valve to open, and the desired amount of fluid combustible is injected into the engine cylinder. Continuing to turn the engine, the battery circuit at the point controlled by the timer is 95 broken, the valve G closes, and then, the ignition circuit (not shown in Fig. 1) being established through the ignition or spark timer E, the point of ignition is 100 reached and the charge is fired, from which time the procedure goes on automatically. As before stated, in Fig. 1, I have indicated the ignition apparatus by a spark timer E. In Fig. 2 it is indicated additionally by the ignition plugs P P', and by circuit connections, having induction coils, the primary coils of which are in a battery circuit including the contacts of the spark timer E (which are arranged very much as the contacts of the valve timer D) and the secondary coils of which are each in a derived or 105 high tension circuit, including its appropriate spark plug P or P', as will be understood without further explanation. It will of course be understood that instead 110 of a high tension ignition system, the low tension system can be employed, the valve timer D being suitably connected to the spark timer of that system.

The valve timer D, as shown in Figs. 4—7, 120 is composed of an outer metallic cylindrical shell or case 1 having an insulating lining 2, in which are embedded metallic contact strips 3—in this instance six in number—equally spaced apart and each electrically 125 connected to its own binding post 4 on the exterior of the case. The case rests on a suitable support S, and is centered upon the shaft I which passes axially through its top and bottom with a sliding fit, the case 130

thus being capable of both up and down movement and rotary movement upon the shaft I. Upon a portion of said shaft within the case is mounted the rotating hub of the timer, consisting of a cylindrical band 5 of insulating material keyed on shaft I and an enveloping sleeve 6 of brass or other conducting material, adjustably secured to the band 5 by set screws 11 and electrically connected to a binding post 7, Fig. 4, upon the exterior of the case 1 by a spring-pin contact of any ordinary or suitable type, indicated by dotted lines at 7', Fig. 4, and also at 7', Fig. 5, wherein only the inner end 15 of said contact appears. Upon the sleeve 6 is a contact which bears with yielding pressure against the lining 2 and, during the revolution of the sleeve 6 with the shaft I on which it is mounted, makes contact with the successive contact strips 3 embedded in 20 said lining. The yielding pressure contact consists in the present instance of a thin metallic roller 8, Fig. 5, mounted on the free end of an arm 9 which is hinged at its other 25 end to the sleeve 6 and is outwardly pressed by a spring 10, so as to hold the roller in yielding contact with the interior of the case.

The contact strips 3 are wedge shaped, 30 large end uppermost, with one vertical edge and one inclined edge, and they are so positioned relatively to the direction of movement of the contact roller 8 (which revolves with shaft I in the direction of the arrow, 35 Fig. 5) that the roller meets each strip at its inclined edge and quits it at its vertical edge. By reason of this arrangement the contact roller 8, always leaves each strip 3 at the same predetermined instant in each 40 revolution, but the time of its meeting the strip is variable and dependent upon what portion of the strip the roller meets. If the case 1 is raised a narrower portion of the strip is brought opposite the roller and consequently the two meet at a time proportionately later, than they would if the 45 broader part of the strip were presented to the roller, and consequently the duration of contact between the parts is correspondingly 50 abbreviated—the length of duration of contact determining the duration of the opening period of the injection valve and consequently the quantity of fluid combustible injected into the engine cylinder.

55 The sleeve 6 is adjustable rotatably upon the insulating band 5, and is fixed in its adjusted position by set screw 11 or other suitable means. It is made thus adjustable to determine the relation which injection 60 should bear to sparking, that is to say to determine the time which should intervene between the injection of the combustible and the sparking. For this purpose it is adjustable with reference to the spark timer E, so 65 as to operate the injection valve at such in-

terval of time before the sparking takes place as may be desired. But when once thus adjusted, this predetermined relation of the valve timer and spark timer must be maintained. To this end the valve timer 70 and spark timer are so interconnected that any rotary movement of the shell or case of the one will cause a corresponding movement of the other. This interconnection may be effected in any suitable way. As a 75 convenient means for the purpose I fix vertical rods 12 to diametrically oppositely located lugs 13 on the exterior of the case 1 of the valve timer which pass down with an easy sliding fit through corresponding lugs 80 14 on the spark timer E below. In this way when the case of the spark timer is revolved more or less to "advance" or "retard" the spark, the case 1 of the valve timer will partake of this movement, without however interfering with its capacity to move up and down independently of the spark timer.

The up and down movement of the case of the valve timer can be effected by hand, as for example by a lever 14' pivoted to a 90 standard attached to the support S (Figs. 2 and 4) and provided with a semicircular yoke 15, armed at its outer ends with pins 16 which project into an annular groove 17 on the case. Or this movement may be effected automatically, as by a ball governor 17 (Fig. 4) mounted on the revolving shaft I, and having its arms connected to a collar on the top of the case 1, as seen in Fig. 4. As the speed of the engine increases and shaft I revolves more rapidly, the case 1 of the valve timer will be lifted, with the effect of correspondingly shortening the duration of contact between the roller 8 and successive contact strips 3.

I remark here that in practice the operating handles of the valve and spark timers, as well as the switches s will all be grouped at the central point of control where they will be within convenient reach of the operator.

100 The electro-magnetic valve G consists of a fluid tight case 18 in which is housed securely a solenoid, the coil 19 of which is properly connected by terminals with the outside circuit controlled by the valve timer D. At one end of the case G is a chamber 23 which communicates with the accumulator B so as to be constantly filled with the fluid combustible at accumulator pressure, and has an outlet 24 into the engine cylinder controlled by the cone valve 22 on the lower end of the divided core 20 of the solenoid, the core being divided into two parts between which is interposed a spring 115 21 which tends to hold the valve 22 down in its seat so as to close the opening 24. When the circuit through the solenoid is closed the lower movable portion of the core is drawn up into the core against the 120 125 130

stress of the spring 21, thus opening the valve.

The extent of lift of the valve, and consequently the size of the valve opening can be regulated by a nut 25 which is microscopically adjustable on the screw threaded valve stem, and is held in adjusted position by lock nut 26—this nut bringing up sooner or later against the head of the solenoid coil, according to its adjustment on the stem. This provision for adjustment of the size of the opening of the valve while leaving the time of its opening undisturbed, enables the feeding, in a multicylinder engine, of differing quantities of combustible to different cylinders and maintaining this difference through any variation in the rate of total supply.

It is desirable to introduce between the accumulator and the injection valves a filter as indicated at 27, Fig. 2. Automatically operating check valves are also introduced at convenient points in the piping systems as indicated diagrammatically at *v* in Figs. 1 and 2.

Hand switches *s s'* may be used to suspend or restore the electrical current to any given injection valve in a multicylinder engine, thus cutting out and restoring at will the cylinder to which that valve pertains.

In lieu of electro-magnetic injection valves I can use mechanically operated valves, getting their periodical opening and closing movement from some moving part of the engine through a suitable system of cams and connecting rods. I prefer, however, the electro-magnetically operated valves. For the sake of clearness I have represented the valve timer as included in a circuit having its own separate battery. But it will of course be understood that the same battery can be used for both the valve timer circuit and the usual "spark" timer circuit.

Having described my improvements and

the best way now known to me of carrying the same into effect what I claim herein as new and of my own invention is as follows:

1. In an explosion engine of the type specified, the combination with the engine cylinder, a force pump driven from the engine, an accumulator to receive the fluid combustible from the pump, adapted to maintain a constant pressure of the combustible greater than the cylinder pressure, a by-pass for returning from the accumulator to the pump the excess of fluid, a passage from the accumulator to the cylinder, and a valve interposed in said passage, of means automatically variable to open said valve sooner or later during each cycle of movement, and means for automatically closing said valve at the same instant of time in each cycle, irrespective of variations in the time of opening the valve, substantially as and for the purposes hereinbefore set forth.

2. In an explosion engine of the type herein specified, the combination with the engine cylinder and, sparking devices, including means for advancing and retarding the spark, of devices for injecting the combustible into the engine cylinder, including means adjustable independently of the sparking devices for completing the injection of the combustible at an instant of time which shall bear any desired relation to the instant of sparking, and connections between the said injecting and sparking devices whereby said relation shall be maintained unchanged by any advance or retardation of the spark, substantially as and for the purposes hereinbefore set forth.

In testimony whereof I affix my signature in presence of two witnesses.

THOMAS T. GAFF.
